Henry Walter Mitchell, Lake Forest, Ill., assignor
to Warner-Patterson Company, Chicago, Ill., a
corporation of Illinois

Application May 7, 1941, Serial No. 100,829

Term of patent 14 years

To all whom it may concern:

Be it known that I, Henry Walter Mitchell, a citizen of the United States of America and a resident of Lake Forest, Lake County, Illinois, have invented a new, original, and ornamental Design for a Solvent Distributing Device and Bracket Therefor, of which the following is a specification, reference being had to the accompanying drawing, forming a part thereof.

Figure 1 is a top plan view of a solvent dis-

tributing device and bracket therefor showing my new design.

Figure 2 is a perspective view of the same.

Figure 3 is a bottom plan view of the same.

I claim:

The ornamental design for a solvent distributing device and bracket therefor, substantially as shown.

HENRY WALTER MITCHELL.
